ART OF INLAYING SHEET MATERIAL

Per F. Skoog, Olympia, Wash.

Application April 28, 1945, Serial No. 590,929

2 Claims. (Cl. 154—104)

1

This invention relates to the art of inlaying sheet material and, more particularly, is a method of patching veneer sheets by the removal of a marred area and its replacement with patching stock, wherein the patch may be adhesively held in place.

Hereinafter my invention is more fully described in accordance with its application to the veneer and plywood industry by way of fully exemplifying the method and the steps in its operation. It will be understood of course that this invention is applicable to many industries wherein it is desirable to inlay sheet material with non-integral portions such, for example, as in producing decorative designs.

In the prior art, it is known to punch-cut sheet material and to place therein patches which occupy the space left by the displaced portion, usually a marred area. In my earlier Patent No. 2,336,703, entitled "Method of patching veneer sheets," and in Patent No. 2,336,704, entitled "Means for patching veneer sheets," I have taught a process, and a mechanism for practicing that process, whereby a sheet is clamped about the area to be punch-cut, the area is punch-cut, a plug is cut and inserted into the opening previously formed, all without the sheet having been unclamped and while maintaining the insert plug against buckling and edgewise expansion. In this process, it was earlier deemed necessary to include a step of disposing of the debris, removed from the sheet, prior to the cutting of a patch portion. The inclusion of this step necessarily required a time interval for such disposal. The method also included time in the operation for the placement of patching stock to be cut to the size and shape of the opening about to be filled. I have since determined that not only can the operation be conducted more expeditiously, but that better results can be obtained by eliminating these steps during the main inlaying operation.

In my earlier process, the mechanism and the method did not include gluing the patching portion into the punch-cut opening, which is considered very desirable by the plywood industry for several reasons, among which is the one that in facing sheet material it is desirable that the line of joinder between the sheet and the patch therein be sealed so that, subsequently, during

the laying-up of plywood when the adhesive between the various plys is quite fluid and the pressure is great, the normally darker colored adhesive will not be forced out through the joint and discolor the face of the exterior surface ply. It is also desirable to seal the fibers between the patch and the sheet at the line of joinder so that subsequent exposure of the plywood to moisture and weather conditions would not be marked by 10 a raising of the grain and a deterioration at the edge of the joint.

I do not intend to detract from the importance of the advantages obtained by my earlier inventions because they are still fully useful under 15 many conditions, including those wherein core stock is being patched and those where surface stock is being patched and the objection to discoloration or grain raising is negligible.

Having in mind, however, the disadvantages 20 of the prior art patching methods, it is an object of this invention to provide a process in the art of inlaying sheet material that may be practiced with greater speed than has heretofore been possible.

25 Another object of my invention is to provide, in a process of the type described, a series of steps which may include the sealing or adhesive joining of the edges of the patch and the sheet material in which the patch is placed without 30 undue hand labor or the employment of unduly complicated mechanisms.

A still further and more specific object of my invention is the provision, in a process of the type described, of the step of applying an adhesive 35 to the walls of the opening immediately in advance of and simultaneously with the movement of the inlay member into the opening without adhesive having been previously applied to the patching member; and also to apply the adhesive in a brushing action for complete distribution.

Still another object of the invention is to include, in a process as mentioned above, the steps of disposing of the debris of the punch-cutting 45 operation and of positioning patching stock during unclamped periods of the operation and to shorten the period required for cutting the sheet material and placing the patch.

The foregoing objects and others ancillary thereto I prefer to accomplish as follows:

According to a preferred embodiment of my invention, I patch veneer sheets having a marred area by clamping the sheet around the marred area and then punch-cutting the marred area from the sheet. Sequentially, by clamping an oversize piece of patching stock to the cut-out marred area, a patch is cut to the size and shape of the punch-cut opening in the sheet material. Next the patch is inserted into said opening, while simultaneously therewith and immediately in advance of the patch, an adhesive is spread upon the walls of the opening, followed by an unclamping of the sheet and the patch. During the unclamped period I remove the cut-out portion and position, for the next cycle of operation, additional oversize patching stock for subsequent use. The importance of maintaining the sheet and the patch stock securely clamped from before initial cutting until after placement of the patch in the opening in the sheet is discussed in the patents mentioned above. The inclusion of the glue-spreading step and the elimination of the debris-disposing step during the actual inlaying operation, are real advantages that are gained in accordance with this new method.

The novel steps that I consider characteristic of my invention are set forth with particularity in the appended claims. The invention itself, however, both as to its organization and its operation, together with additional objects and advantages thereof, will best be understood from the following description of specific arrangements of steps, when read in connection with the accompany drawings, in which:

Fig. 1 is a view disclosing an arrangement of mechanism capable of practicing my method, which mechanism appears in the neutral position;

Fig. 2 is a view similar to Fig. 1 as the mechanism appears after the sheet material is punch-cut and before the patching stock is cut;

Fig. 3 is an enlarged detail view of the operation of the insertion of a patch and showing the spreading of the glue in advance and simultaneously with the movement of the patch; and

Fig. 4 is a perspective view of a fragment of patched veneer.

A patching method useful in the art of inlaying sheet material and to overcome the disadvantages hereinbefore encountered and enumerated above, must have at least two totally distinct characteristics: it must be capable of being performed in a shorter space of time than has previously been possible; and it must also produce inlaid pieces in sheet material which pieces are securely held in place and the joints of which, with the sheet, may be sealed or adhesively joined and will not leak or deteriorate in use. Accordingly, a preferred embodiment of my invention, referring to the figures of the drawing, is practicable by the mechanism therein disclosed.

The numerals 12 and 14 designate opposed frame members, or arms, that are part of a larger bifurcated frame more fully disclosed in my Letters Patent No. 2,336,703, entitled "Method of patching veneer sheets," and No. 2,336,704, entitled "Means for patching veneer sheets." Preferably, the arms are superpositioned and have, respectively, axially aligned passages 13 and 15, in which are mounted the reciprocal punch-cutting means and between which are passed the veneer sheets and the patching stock during inlaying operations.

Within the opening or passage 13, is the recip-

rocally movable die 16, which carries the punch 18 having cutting edge 19. A veneer sheet V is punch-cut when the punch is moved through the aligned opening of backing member 20. Punch 18 comprises a patch-shaped block having stem 21 which is removably secured in a recess, provided in the ram 16, by means of screw 22. The cutting edge 19 is usually annular and has a tapering inner face forming a wall of recess 23, in which the cut-out portion of the veneer sheet is retained when cut.

Recess 23 also encloses the flanged head 24 of plug member 25. The periphery of head 24 is slightly undercut and lies in spaced apart relation around the periphery with respect to the lower or bottom face of cavity 23. In plug 25, in a suitable cavity provided therefor, is seated the ejector 26, pressed by spring 27, which is useful in ejecting from the cavity 23 a cut-out portion of a veneer sheet which may be disposed therein.

During an inlaying operation, glue, adhesive, or sealing material is supplied to coupling 30 which is vertically movable with the ram 16 in slot 31. Such glue passes from the coupling 30 through passage 32 into passage 33 in stem 21, and thence to chamber 34 in the punch 18 under the plug 25. A plurality of passages 35 extend from chamber 34 to orifices near the edge of the cupped recess 23 and under the periphery of the head 24. Glue is applied to coupling 30 from tank T by means of pump 37 that is periodically actuated by the cam 38 at a timed point in the inlaying sequence.

Because it is important that the veneer sheet 35 V be clamped during the operation of removing the cut-out portion, a die ram 40, reciprocally mounted in the passage 15, is provided to move into clamping position against the back-up plate 28 and to clamp the veneer sheet therebetween. The ram 40 is shaped as a hollow cylinder with side openings 41, 41, aligned to provide a passage therethrough. The lower face of ram 40 comprises both a clamping member and a female die member shaped to accommodate punch 18 and punch 48, the former working against the bottom 45 and the latter against upper cutting edge 42.

By means of a pair of feed rolls 44 and 45, patching stock P is fed into the die ram 40 through the openings 41, 41, in order to position 50 the patching stock relative the cutting edge 42 for the cutting of a suitable insert or inlay plug member.

Patching strip P is cut to form an inlay member I by means of the inlay punch 47, which is carried on the lower end of the reciprocal punch ram 48. The inlay punch contacts, in its descending travel, the upper face of strip P and forces a portion of the same downward against the cutting edge 42 and thence through passage 43 and into the veneer sheet, as will be more fully described hereinafter.

The steps of the operation are sequentially illustrated in Figures 1, 2 and 3. In Fig. 1, the mechanism is shown in the neutral position, with the veneer sheet, as well as the strip P, unclamped. Both rams 16 and 48 are in the retracted positions. In Fig. 2, the punch 18 has been moved upward through the veneer sheet V and has had cut therefrom portion D, constituting the debris of the operation. Portion D lies in cavity 23 and, with the backing head 24, fills cavity 23 to provide a flush backing against the strip P when the patch or inlay is cut upon a downward stroke of ram 48 and punch 47 past

edge 42, and while the same is passed through opening 43 of die ram 40.

The edge of portion D, as appears in the enlarged showing of Fig. 3, has been slightly tapered or compressed by means of the inner sloping face of recess 23. Cut-out D rests upon head 24 in close juxtaposition. By this arrangement, it is to be noted, during the cutting of the veneer sheet, the same is clamped between members 20 and 40, and also the patch or insert I, after cutting, is at all times clamped between debris D and the male punch 47.

In Fig. 3, the insert I is shown as about to move into the opening formed in sheet V. As this occurs, pump 37 is actuated by cam 38 and a small, measured amount of the fluid is forced through passages 32 and 33, chamber 34, and into the passages 35, to be discharged, under pressure, to immediately below the edge of head 24. The glue escapes between the sloping wall of the recess 23, and the edge of the debris D and is wiped in a spreading action upon the wall of the previously formed opening in the sheet V. This application of adhesive or sealing material to the opening being inlaid is accomplished simultaneously with the insertion of the inlay and immediately in advance thereof, as the same moves into the opening. Since the fibres at the edge of the debris portion D tend to drag over the edge 19 of punch 18, they act as a brush and sweep over the wall of the sheet opening in a manner to assist distribution of the adhesive and to force the same into the cavities of the wood walls. Since the glue is under pressure during the inserting period, it will tend to flow into any cavities within its path, but the brushing action serves also to restore the fibre structure in the wall of the opening more or less to normal.

It is to be noted that the fibres in the opening wall are usually bent by the lower cutter during the punch-cutting of the sheet V, and that they will be bent oppositely by the insertion of the plug as it is forced into the opening. Under such conditions, the fibres of the inlay plug and of the sheet tend to interlock. In the presence of the adhesive, a secure and sealed joint will be formed. This joint has considerable strength, and produces perfect mating or alignment of the outside faces of the inlay and the sheet. During the insertion of the inlay plug I, even though there is glue being applied to the walls of the opening, the periphery of the debris portion D serves to protect the inlay from being smeared with glue, since D has an upper dimension that is the same as the inlay, because the two are cut to exactly the same dimensions on mating die elements.

When the inlay I is properly placed in sheet V, the ram 16 is caused to retract downward and ram 48 will be similarly retracted upward, in the opposite direction. The pressure is thus removed from portion D, the spring pressed ejector 26 acts to shove the debris out of recess 23. A blast of air passing through conduit 50 into the space above the punch 18 picks up the debris and blows it out through opening 51.

With the ram retracted to approximately the position shown in Fig. 1, the rolls 44 and 45 are rotated to feed forward an additional portion of the strip P for subsequent cutting of another inlay plug or patch during the next inlay sequence. It is also during this portion of the cycle that the operator shifts the sheet material for the next inlaying or patching operation.

The movement of the various rams, dies, and

clamping members, as well as the injection of glue, the operation of the air blast to remove the debris, and the indexing forward of the veneer strip P, are all accomplished by suitably timed operating mechanisms, as is more clearly disclosed in the Letters Patent mentioned above.

It is preferable in the operation of the method herein described to employ a glue, filler, or sealer material, which is preferably uncolored, and which will serve to seal the joint as well as to cause the inlay to adhere in the opening in which it is placed in the sheet material.

This method is particularly applicable to the treatment of external plies of sheet material, since the ordinary blood-colored glues employed in the adhesive industry may be safely applied between the inlaid facing sheet and the adjacent core layer, and the whole may be bonded together with the usual high pressure and heat customary in the industry, while none of this colored adhesive, interior of the sheet, will be forced through the sealed joint between the patch and the opening. Thus is avoided discoloration of the face of the sheet, which would otherwise be unsightly and tend to down-grade the finished plywood. There is another important reason for adhesively joining or sealing the inlay into the sheet, and that is that the bonding agent serves to prevent the ends of the fibres from raising in the joint between the inlay and the sheet after it has been exposed for some time to the weather.

In Fig. 4, the fragment of veneer sheet V is shown with patch P in place following the completion of the operation depicted as beginning in Fig. 3 and with the clamping pressures released. In this instance, the patch is shown as a "boat-shaped" patch, conventional in the plywood industry, because of its ability to blend with the grain of the main sheet. However, from a mechanical standpoint, I have found it desirable, although not necessary, to blunt the ends of the patch to provide easy fitting of the patch to the veneer and to avoid sharp pointed dies.

While I have shown and described particular embodiments of my invention, it will occur to those skilled in the art that various changes and modifications may be made without departing from the invention, and I therefore aim in the appended claims to cover all such changes and modifications as fall within the true spirit and scope of my invention.

Having thus described my invention, I claim:

1. In the art of patching veneer, the method, comprising: perforating said veneer at the point to be patched to provide an opening having walls perpendicular to the faces of said veneer, unidirectionally wiping a coating of adhesive under substantial pressure on the walls of said opening in a motion withdrawing from one edge of the opening to the other, simultaneously therewith inserting a patch piece equal in size and shape to said opening thereinto by causing the same to move and follow in the same direction the wiping application of the adhesive coating in immediate sequence, and terminating said movement of the patch piece when the same is in substantial alignment with at least one face of the sheet material surrounding said opening.

2. In the art of setting a pre-formed inlay member into a similar sized opening through sheet material, the method, comprising: unidirectionally wiping a coating of adhesive under substantial pressure on the walls of said opening in a motion withdrawing from one edge of the opening to the other, simultaneously therewith inserting

ing the inlay piece into the opening by causing the same to move and follow in the same direction the wiping application of the adhesive coating in immediate sequence, and terminating said movement of the inlay piece when the same is in substantial alignment with at least one face of the sheet material surrounding said opening.

PER F. SKOOG.
